(57) **CLAIM**

The ornamental design for a display assembly in handheld state, as shown and described.

DESCRIPTION

FIG. 1 is a perspective view of a display assembly in handheld state showing the inventive design.

FIG. 2 is a front view of said display assembly in handheld state showing the inventive design.

FIG. 3 is a rear view of said display assembly in handheld state showing the inventive design.

FIG. 4 is a left side view of said display assembly in handheld state showing the inventive design.

FIG. 5 is a right side view of said display assembly in handheld state showing the inventive design.

FIG. 6 is a top view of said display assembly in handheld state showing the inventive design.

FIG. 7 is a bottom view of said display assembly in handheld state showing the inventive design; and,

FIG. 8 is a second perspective view of said display assembly in handheld state showing the inventive design.

The broken lines in the figures depict portions of the display assembly in handheld state that form no part of the claimed design.
